UNITED STATES PATENT OFFICE

JOHN STERLING GULLBORG, OF CHICAGO, ILLINOIS, ASSIGNOR TO ALEMITE DIE CAST-
ING & MFG. CO., OF WOODSTOCK, ILLINOIS, A CORPORATION OF DELAWARE

DESIGN FOR A HANDLE ESCUTCHEON FOR AUTOMOBILE HARDWARE OR THE LIKE

Application filed September 11, 1930. Serial No. 36,938. Term of patent 3½ years.

To all whom it may concern:

Be it known that I, JOHN STERLING GULLBORG, a citizen of the United States, residing at Chicago, in the county of Cook and State of Illinois, have invented a new, original, and ornamental Design for a Handle Escutcheon for Automobile Hardware or the like, of which the following is a specification, reference being had to the accompanying drawing, forming a part thereof.

Fig. 1 is a front elevation of the handle

escutcheon for automobile hardware or the like showing my new design;

Fig. 2 is a lateral elevation thereof; and
Fig. 3 is an end elevation thereof.

I claim:

The ornamental design for a handle escutcheon for automobile hardware or the like as shown.

In witness whereof, I hereunto subscribe my name this 5 day of September, 1930.

JOHN STERLING GULLBORG.
